ATTORNEY.

UNITED STATES PATENT OFFICE.

JOSEPH LOEB, OF PHILADELPHIA, PENNSYLVANIA.

DESIGN FOR FRINGE.

SPECIFICATION forming part of Design No. 13,701, dated March 6, 1883.

Application filed December 16, 1882. Term of patent 3½ years.

To all whom it may concern:

Be it known that I, JOSEPH LOEB, a citizen of the United States, residing in the city and county of Philadelphia, State of Pennsylvania, have invented and produced a new and original Design for a Fringe, of which the following is a specification, reference being had to the accompanying drawing, forming part thereof.

10 The accompanying drawing is a face view of a section of fringe embodying and illustrating my design, which consists of a fringe having a heading, A, of any suitable kind, to which are attached at intervals chenille pendants B. The middle portion of each pendant is formed of blocks or stripes of different colors, so that the fringe presents throughout its length at the middle a striped band, C, with the following characteristics: a central stripe,

15 a, having borders b of narrow stripes, the portions a' and b', respectively above and below the borders, being similar, producing plain

bands on opposite edges of the middle striped band, C.

The stripe c may or may not form part of the design.

I do not confine myself to the use of any given color or material.

I claim—

1. A design for a fringe, consisting of a heading and a series of chenille pendants, having at the middle of the pendants a stripe, a, and borders b therefor of narrow stripes, substantially as set forth. 30

2. A design for a fringe, consisting of a heading and a series of chenille pendants, having a middle stripe, a, with borders b of narrow stripes, and plain bands a' b' on opposite edges of said borders, substantially as set forth. 35

JOSEPH LOEB.
